UNITED STATES PATENT OFFICE.

JEFFERSON D. ANDERSON, OF BLUE MOUNTAIN, MISSISSIPPI.

DESIGN FOR AN ICE-CREAM MOLD.

SPECIFICATION forming part of Design No. 31,256, dated July 18, 1899.

Application filed June 20, 1899. Serial No. 721,251. Term of patent 7 years.

To all whom it may concern:

Be it known that I, JEFFERSON D. ANDERSON, a citizen of the United States, residing at Blue Mountain, in the county of Tippah, State of Mississippi, have invented and produced a new and original Design for Ice-Cream Molds, of which the following is a specification, reference being had to the accompanying drawings, forming a part thereof.

Figure 1 is a top plan of the mold. Fig. 2 is a section on the line 2 2, Fig. 1.

As shown in the drawings, the novel mold is essentially a shell circular in plan view and having its base plane and its upper wall upwardly convex.

What I claim is—

The design for an ice-cream mold, substantially as shown and described.

JEFFERSON D. ANDERSON.
